UNITED STATES PATENT OFFICE

JOHN S. GREENE, OF ROCHESTER, NEW YORK, ASSIGNOR TO PHOTOSTAT CORPORATION, OF PROVIDENCE, RHODE ISLAND, A CORPORATION OF RHODE ISLAND

PHOTOGRAPHIC DEVELOPING METHOD AND APPARATUS

Application filed December 28, 1927. Serial No. 243,181.

My present invention relates to photography, and particularly photographic copying machines of the nature in which a continuous roll of sensitized photographic paper or film is exposed in sections, the sections severed and the separate prints thus formed, manipulated in baths by which they are developed and fixed, and the invention has for its general object to provide an efficient and serviceable machine of this nature wherein the prints will be successively picked up with sureness and precision and rapidly and safely carried through the bath or baths. The improvements are directed in part to the arrangements for presenting the print to the carrier; to the driving and control of the carrier, whereby the prints will each be properly treated in the baths, and to mechanism through which the prints are finally stripped from the carrier and deposited at the appointed place.

Another object of the invention is the provision of apparatus which will deliver a developed photographic print face upwardly in a fixing or hypo bath which is open and readily accessible to the operator, so that he may look at the print to see whether or not it is satisfactory without placing his hands in the bath to turn the print over to expose its face.

Still another object of the invention is the provision of an improved method of developing photographic prints, and particularly of one by which a print may be placed face upwardly in a fixing bath exposed to actinic light, without danger of spotting or discoloring the print.

To these and other ends the invention resides in certain improvements and combinations of parts, all as will be hereinafter more fully described, the novel features being pointed out in the claims at the end of this specification.

In the drawings:

Figure 1 is a side elevation of a photographic copying machine constructed in accordance with and illustrating one embodiment of my invention;

Figure 2 is an enlarged fragmentary view of a portion of the opposite side of the ma-

chine showing the driving devices and control box;

Figure 3 is a fragmentary central longitudinal section through the developing portion of the machine, an adjacent portion of the exposing means being shown in elevation;

Figure 4 is an enlarged fragmentary view of the upper or fixed pan shown in Figure 3, with the parts in a different position;

Figure 5 is a similar view with the parts in still another position;

Figure 6 is a top plan view of a portion of this same mechanism, while the parts are in the position of Figure 5;

Figure 7 is a transverse section taken on the line 7—7 of Figure 5;

Figure 8 is a similar section taken on the line 8—8 of Figure 4;

Figure 9 is an enlarged section through one of the bars of the immersing frame,

Fig. 10 is an elevation of the driving mechanism with the cover of the gear box removed to show the interior parts.

Similar reference numerals throughout the several views indicate the same parts.

The following description is specific only to the particular machine illustrated as an embodiment of the invention in the drawings, and to first give a general idea of the machine there disclosed, I may say that it embodies a usual form of camera, the severed prints from which are dropped through a chute to a vertical position in which the advanced edge lies in the path of an endless conveyer, or carrier element, provided with a plurality of bars having impaling pins. The bars each

successively pick up a print and carry it successively through three baths, so that there are three prints in various stages of treatment on the carrier at one time. The cycle of travel is divided into three parts between which there is a pause in the movement of the carrier. During the first two pauses the print occupies the developing bath and the washing bath respectively. During the last pause it is stripped by a special mechanism and immersed in the final fixing bath. Suitable mechanism is employed for driving the conveyer and automatically stopping it at the appointed positions of the pin bar to

bring about this result. Each actuation of the driving mechanism by the operator takes the carrier through one-third of its cycle, and it does not move again until the operator trips it. The prints are fed from the exposing member to the developing mechanism one by one by an independent manual operation, and thus by alternately operating his camera mechanism and his developing mechanism the process is made practically continuous, and but one print at a time appears at the pick up point in the path of the carrier and the impaling bar that is approaching that station.

10 Referring more particularly to the drawings, and particularly to Figure 1 thereof, 1 indicates a camera body 1 slidable for focusing on rollers upon an open frame work table 2 by means of a rack and pinion mechanism operated by the knob 3. The body is connected by the usual bellows 4, with a stationary front 5 carrying the lens and prism 6 that carry the image to the focal plane of the camera of an object resting upon a copy board 7 which is usually vertically adjustable, the focusing being accomplished through the aforesaid movement of the camera body 1.

20 As indicated in dotted lines, the body 1 contains a film roll 8 which is drawn into the focal plane as at 9 by feed rolls 10. When a section is exposed it passes down to the developing part of the apparatus in the position shown at 11 in Figure 3, and being severed by the knives indicated generally at 25 12 in that figure becomes a separate exposed print.

25 Referring to Figure 3, when the print 11, as before stated the camera body 1 is slidable on the frame 2, and carries with it the entire developing apparatus, they together forming a unit as shown in Figure 3. Before describing this unit in which my invention principally resides and to complete the brief general description of the machine as shown in Figure 1, 13 indicates a tank compartment or casing depending from the body 1, and supported on the top rail of the frame 2, which casing encloses the developing apparatus. Access is had thereto at the side through a door 14 through which the fixing 30 bath or tank may be removed as will be later referred to, and the under portions 15 and 16 constitute respectively the developer tank and the water tank wherein the prints are washed before passing up for fixation. These 35 two tanks may be emptied when desired by means of cocks 17 and 18 into a drainage trough 19 which runs the length of the machine. On the camera body, 20 is the winding feed handle and 21 is the cut off handle, 40 whereas on the developing casing 13, 22 is the handle which, when depressed, trips the driving means for the carrier before referred to and later to be described in detail.

45 Referring to Figure 3, when the print 11, as before described, reaches the position of

that figure it is held in a chute 23 depending from the camera body. The lower end of this chute is open rearwardly with an inclined bottom 24 between rearwardly extended side portions 25 that terminate in an abutment plate 26 extending across the chute from side to side. The advanced or lower end of the print is arrested by this abutment plate, so that the tip of it is curled or partially horizontally disposed. The endless carrier provided with the impaling devices that pick up the print passes between the extended side portions 25 of the chute and between the body of the latter and the abutment plate 26. We will call this the pick up point A.

50 The conveyer consists in the present instance of two endless chains 27 arranged one near each side of the casing, and running over a number of sprockets, rolls, or similar devices 28, carried by transverse shafts 29, 85 or on studs 30 on the side walls. The character and arrangement of these sprockets is too clear from an inspection of Figure 3 to warrant specific description, the object being of course merely to guide the conveyer in a 90 certain path that will be described as such. At equal intervals the chains are spanned and connected by print carrying bars 30 (see Figure 6) provided with impaling pins 31 projecting in the direction of travel of the 95 conveyer which is indicated by the arrows. The path of these pin bars during a cycle of movement of the conveyer is as follows:

At the pick up point A at the end of the chute the pin bar which has reposed at station D starts downwardly upon the depression of lever 22, and for reasons hereinafter described, impales the lower end edge of the exposed and severed print 11 in the chute, which print has projected itself between the 1 chains under the pin bar. The pin bar drags the print into the developing tank 15, where it goes around the lower sprocket therein and, after rising a short distance, stops at what we will call station B as indicated. 1 The print having trailed behind it is thus submerged in the contents of the tank and developed. If long enough, it will be in a doubled condition, the tank being separated into two parts by a central wall 32 to segregate 1 the downwardly and upwardly moving elements. Upon the next actuation the pin bar travels upwardly out of the tank and over roll 33, in connection with which operates a squeegee roll 34 that wrings the excess developer from the print and draws it back into the tank. It thence passes beneath a jockey roll 35 and down into tank 16 in crossing which it travels upwardly over a raised roll 36, acting in conjunction with which is a roll 37 used to prevent any overrun of the print due to inertia as the pin bar stops suddenly at station C and is more important because the print is now in tank 16 in which the rolls are submerged, and subject to float-

ing action. The pin bar finally comes to rest at the point indicated and which we will call the washing station C. The print carried by the bar remains in this submerged condition, and is washed of developer and made temporarily impervious to or unaffected by light, while the succeeding print is held submerged at developing station B. Upon the next actuation the pin bar travels straight 10 upwardly and then forwardly over the elevated fixing tank 38 to the forward end of which it proceeds, trailing the print behind it in the hypo or fixing solution contained in tank 38. It finally makes an abrupt turn 15 around the forward one of two closely associated sprockets 28a and 28b and comes to rest between them with its impaling pins reversed to a rearwardly and downwardly projecting position. At this point the print 20 is stripped off in a manner hereinafter described, while the pin bar is stationary at what we will call stripping station D. Upon the next actuation the pin bar returns to pass point A as before and to pick up another 25 print as it goes by.

It is to be understood that the pin bar comes to rest only at stations B, C and D. It is moving continuously at A, but this point has, for convenience, been included in 30 the series because of its importance in the cycle, and in order to logically trace in the description the progress of the print from the time it is picked up to the time that it is deposited.

35 While the carrier chains 27 are traveling horizontally the long distance over the fixing pan 38, they are prevented from sagging by being supported upon tracks 39 (Figs. 3, 7, and 8) which are formed by inturned flanges 40 on the sides of the casing 13.

The pan 38 for the fixing bath is supported upon a shelf 40 within the casing, and is removable as can be clearly seen from Figs. 7 and 8 through the door 14 shown in and 45 previously described with reference to Fig. 1. The prints, however, are removed through the open top.

Power for driving the conveyer is derived from a motor 41 (Fig. 2) suitably mounted 50 on one side of the tank compartment 13. It drives the shaft 29a which is just above the developing tank 15 through an automatic stop mechanism contained in the casing 42.

This mechanism may be of any suitable 55 form, such for example as that shown in the copending application of Arthur W. Caps, filed December 28, 1927, for timing mechanism, Serial No. 243,081, now Patent No. 1,791,555, issued February 10, 1931. Reference may be had to this patent for a more 60 complete description of one suitable form of timing or automatic stop mechanism.

Referring now to Fig. 10 of the present 65 drawings, the stop mechanism may comprise in general a shaft 65 constantly driven by

the motor 41 and carrying a worm 66 meshing with a worm gear 67 secured to a vertical shaft 68 to which is splined a vertically movable clutch jaw 69. The shaft 43 of the tripping crank 22 (Fig. 1) extends through to 70 the left side of the machine and carries an arm 44 (Fig. 2) overlying a plunger 45 mounted in the gear box 42 so that oscillation of the shaft 43 by the crank 22 results in depressing the plunger 45.

The plunger 45 is normally held in elevated position by a spring 70, but when it is depressed by oscillation of the arm 44, it causes downward movement of a clutch shifter 71 secured to the plunger, which in turn causes a downward movement of the clutch jaw 69 splined to the shaft 68 and brings this clutch jaw into engagement with a lower clutch jaw 72 formed on a sleeve 73 rotatably mounted on the shaft 68. In this way, the force of the driving motor causes rotation of the sleeve 73 and through the spiral gear 74, formed on this sleeve, it drives a spiral gear 75 on the shaft 29a (Figs. 2, 3, and 10) which thus drives the conveyer mechanism.

When the clutch shifter 71 is depressed to engage the clutch, it is automatically held in this depressed position by a shoulder 76 on a latch member 77 pivoted at 78 and normally urged to latching position by a spring 79. Thus the clutch is held engaged even though the actuating crank 22 be immediately released. After the conveyer has been driven a predetermined distance, however, so as to carry a print from one station to the next station, this distance being equal to the spacing from one of the print carrying bars 30 to the next bar 30, the clutch is automatically opened so that the driving of the conveyer ceases until the driving mechanism is once more actuated.

This opening of the clutch is accomplished by suitable timing mechanism, as for example, the pin 80 on the metering gear 81 which, as the gear rotates, 100 engages a nose 82 on the latching lever 77 and moves this lever against the tension of the spring 79 to release the clutch shifter 71 so that the clutch is opened by the spring 70. The metering gear 81 may be driven by the worm or spiral gear 82 formed on the sleeve 105 73. The proportions of the gears 81 and 82 are so chosen with respect to the gears 74 and 75 that the releasing pin 80 on the gear 81 will make one complete revolution when the conveyer has been driven through one stage 110 of its motion to carry any given conveying bar 30 from one station to the next station.

Thus after each actuation of the conveying mechanism, as by oscillating the crank 22, the mechanism will be driven automatically 115 through the distance from one station to the next station, and will then automatically come to rest. In this way, a print which is in the developing bath immediately prior to one actuation of the conveying mechanism 120

will be carried to the washing bath, and will come to rest therein, a print from the washing bath will be carried to the fixing bath and deposited therein, and a print in the chute 23 immediately prior to the actuation of the conveying mechanism will be withdrawn from this chute and carried to the developing bath where it will come to rest.

I will now describe the stripping mechanism for disengaging the print at station D and depositing and submerging it in the fixing bath 38. At the top of the tank compartment 13 which is left open (the shelf 40 acting as a partition to sufficiently cut off light from the developing chamber below) there is arranged a yoke 46 turning on a rearward pivot 47, and embodying a pair of normally forwardly extending arms 48 (Figs. 3 and 6). These arms rest at their forward ends upon small stop brackets 49 above the chain tracks 39. Extending between them and across the tank are two rock shafts 50 and 51 carrying respectively two pairs of depending rock arms 52 and 53. Pivoted supported by the lower ends of these arms is a grille or frame consisting of longitudinal bars 54 through which the pivot rods 55 extend, and cross rods 56. The frame is thus capable of a parallel upward and forward motion in which it rises high up from the position of Figure 5 to that of Figure 4. There is also pivoted to the forward pivot bar 55 the arms 57 of a yoke 58, which normally projects forwardly beyond the frame, and rests in a substantially horizontal position upon a stop rod 59.

As shown in the cross sectional views, the arms 52 at the rear normally hang in the path of the pin bars 30, with the frame 54 below, this position being maintained and a tendency to return thereto being assisted by springs 60, coiled about the ends of the rock shaft 50. It will be observed that the ends of the frame have a sled-like curve, which is tangent at all times to the rear sides of the arms 52.

When, during the last increment of the cycle, a pin bar travels from washing station C towards stripping station D, it engages the arms 52 at the rear, and carries them forward, raising the frame 54 forwardly and upwardly, and the pin bar then passes beneath the frame itself, and holds it in this position, as shown in Figure 4. The paper 11 trails after it, and drops into the bath though still attached. It will be observed that during this travel over the bath the impaling pins of the pin bar are projecting forwardly or in the direction of travel. When the pin bar reaches the forward end of the frame a very rapid action occurs. As it gets to the vertical median of the sprocket 28a, the end of the frame slips from it and, assisted by its spring 60, drops downwardly and rearwardly with a sweeping movement upon the paper or print 11, and into the bath. However, the pin bar is still be-

neath the forwardly projecting yoke 58, which it knocks upwardly as it quickly encircles the sprocket. By the time the pin bar comes to rest at the station D between the two sprockets, as shown in Fig. 5, the main frame has 70 swung back sufficiently to release the yoke 58 therefrom. It slides rearwardly and downwardly in doing so, and scrapes the edge of the paper off of the impaling pins, the direction of which has now been reversed to a 75 rearward and downward inclination, facilitating the disengaging action. Figure 5 shows the position of the elements just at this point.

The paper is submerged by the frame and 80 the swinging contact of the latter with its surface aids in the stripping action, and may at times be sufficient in itself, but the stripper yoke 58 makes sure of this by scraping the paper off of the ends of the pins. 85

The yoke 46 as before stated is pivoted at 47 and may be raised to the dotted line position of Figure 3 to carry the entire immersing and stripping mechanism out of the tank 38, as for the purpose of removing prints 90 from the machine and when removing the hypo tank. In this raised position a gravity latch 61 catches into an edge of the yoke as shown in Figures 3 and 4 to hold it in position. 95

When the immersing frame 54 drops down upon the paper, the latter is usually floating on the surface, and in order to give free and rapid access of the solution to the upper side of the paper, the longitudinal bars of the 100 frame are provided with a series of openings as shown at 62 in Figure 9, and in other figures.

It will be noted from Fig. 3 that when the print 11 is in the chute 23 the face or 105 exposed side thereof is toward the front of the machine or toward the right when viewed as in this figure, and that after it has been drawn through the developing bath 15 and washing bath 16, it will be delivered face 110 upwardly to the fixing or hypo bath 38. This fact of delivery to the fixing bath with the face of the print upwardly, and the fact that the fixing bath need not be in a dark chamber, but may be uncovered and freely 115 accessible to the operator, are important features of the present apparatus. They result in enabling the operator to observe the print to see whether or not it is satisfactory as soon as it is delivered to the hypo bath, without the necessity of removing any covering or light screen from the hypo bath and without the necessity of putting his hands into the bath to turn a print over. 120

If a photographic print be conveyed directly from a developing bath to a fixing or hypo bath, the latter bath must be within a dark chamber, since even very slight exposure of the print to light before it is 125 immersed in the fixing bath will result in bad 130

discoloration thereof, spoiling the print. It has been discovered, however, that if the developer be washed off of the print, such as by the use of the washing bath 16 of the present apparatus, then the print is no longer discolored by momentary exposure to light and it may safely be placed in a fixing bath which is not in a dark chamber but which is uncovered and accessible to light and to the operator of the apparatus. Thus, according to the present invention, the developing bath 15 and washing bath 16 are within a dark chamber so that no light reaches the print after it is developed until it has passed through the washing bath 16. After being washed, however, temporary exposure to light while it is being placed in the uncovered fixing bath 38 is not detrimental. Accordingly, the washing bath 16 may be considered as a means for rendering the print temporarily impervious to or unaffected by light, and it is an important feature of the invention in that it permits the use of an apparatus in which the print is delivered face upwardly to a fixing bath which is not in a dark chamber, but which is accessible to the operator, whereas heretofore it has been usually considered necessary to exclude light from the fixing bath or to deliver a print face downwardly to the fixing bath so that it would not be affected by light.

It should be noted that in order to accomplish the purposes above set forth the print must remain in the washing bath for a substantial length of time. Merely running the print rapidly through a water bath does not have the desired effect of rendering it temporarily unaffected by light so that it could safely be placed face upwardly in an exposed fixing bath. In the present machine it will be obvious from the preceding detailed description that the print remains in the washing bath for substantially the same length of time as it remains in the developing bath, and in actual use this is found to give satisfactory results. Such immersion in the washing bath of about the same length of time as required for developing the print renders it temporarily unaffected by light so that it will not be fogged or discolored by the light entering the fixing bath for the few seconds which elapse before the fixing solution begins to act.

It should further be noted that the endless conveying mechanism in the present apparatus does not at any point come into contact with fixing solution, and thus does not carry any fixing solution into the developing bath, so that contamination of the developer by the fixing solution is entirely avoided. This is important because the developing solution and the fixing solution chemically react with each other in such a way that the developing solution is substantially deteriorated if fixing solution is introduced thereto.

I claim as my invention:

1. In a photographic print treating apparatus, the combination with an exposing mechanism and a fluid bath located below the same, of a vertically disposed light tight chute extending downwardly from the exposing mechanism, said chute being substantially straight for the major portion of its length and having a laterally turned end provided with an abutment against which latter the end edge of a print standing vertically in the chute is adapted to rest, means for feeding prints into the chute from the exposing mechanism and a conveyer having a print carrier thereon movable downwardly substantially parallel with the major portion of the chute and provided with impaling pins adapted to engage the said end of the print and to carry the latter from the chute to the bath.

2. In a photographic print treating apparatus, the combination with a light tight vertically disposed print feeding chute substantially straight throughout its major portion and having laterally projecting extensions of its side portions at its lower end, said extensions carrying an abutment against which the end edge of a print occupying the chute is adapted to rest, of a flexible conveyer movable in a downward path parallel with the chute and passing between the said extensions thereof and between the chute and the said abutment, and a carrier bar spanning the conveyer and provided with impaling pins adapted to engage the print and draw it from the chute.

3. In a photographic print treating apparatus, the combination with a frame and a fluid bath supported thereby, of a conveyer arranged to travel over the bath and to introduce a print therein, said conveyer including means for holding a print, and an immersing device for submerging the print actuated automatically by the conveyer, said immersing device embodying depending rock arms, in the path of travel of and actuated by said means for holding a print and a frame carried thereby and having a parallel motion out of and into the bath as it is respectively actuated and released by the conveyer.

4. In a photographic print treating apparatus, the combination with a frame and a fluid bath supported thereby, said frame being provided with tracks at opposite sides of the bath, of a conveyer arranged to travel over the bath upon the tracks, and to introduce a print therein, said conveyer including means for holding a print, and a swinging immersing device mounted on the frame and depending between the tracks, said immersing device being raised out of the bath by an actuating contact with said means for holding a print.

5. In a photographic print treating ap-

paratus, the combination with a frame and a fluid bath supported thereby, said frame being provided with tracks at opposite sides of the bath, of a conveyer arranged to travel over the bath upon the tracks, and to introduce a print therein, a swinging immersing device mounted on the frame, and embodying rock arms depending between the tracks and carrying a frame, and a print engaging carrier bar on the conveyer adapted, during the travel of the latter, to engage the arms and raise the frame and to then pass in contact with the frame and hold it elevated.

6. In a photographic print treating apparatus, the combination with a bath and a conveyer arranged to travel across the same, and embodying two flexible elements on opposite sides of the bath, of a carrier bar having impaling pins thereon projecting in the direction of travel across the bath, said bar extending between the conveyer elements to span the bath, means near the end of the bath for reversing the travel of the conveyer and reversing thereby the direction of projection of the pins, and means for stripping a print from the carrier bar while the direction of the pins is thus reversed.

7. In a photographic print treating apparatus, the combination with a bath and a conveyer arranged to travel across the same, and embodying two flexible elements on opposite sides of the bath, of a carrier bar having impaling pins thereon projecting in the direction of travel across the bath, said bar extending between the conveyer elements to span the bath, means near the end of the bath for reversing the travel of the conveyer and reversing thereby the direction of projection of the pins, means for stripping a print from the carrier bar, and means actuated by the conveyer for carrying the striping device into operative position.

8. In a photographic print treating apparatus, the combination with a bath and a conveyer arranged to travel across the same, and embodying two flexible elements on opposite sides of the bath, of a carrier bar having impaling pins thereon projecting in the direction of travel across the bath, said bar extending between the conveyer elements to span the bath, means near the end of the bath for reversing the travel of the conveyer and reversing thereby the direction of projection of the pins, and means for stripping a print from the carrier bar operated by the carrier bar itself during its reversing movement.

9. In a photographic print treating apparatus, the combination with a frame, and a fluid bath supported thereby, of a conveyer arranged to travel across the bath and provided with a print carrier, a swinging immersing device normally depending into the bath but adapted to be raised by the conveyer while the print carrier passes beneath

it, and a stripping device on the immersing device adapted to engage and strip the carrier when the immersing device is released.

10. In a photographic print treating apparatus, the combination with a frame, and a fluid bath supported thereby, of a conveyer arranged to travel across the bath and provided with a print carrier, a swinging immersing device normally depending into the bath but adapted to be raised by the conveyer while the print carrier passes beneath it, and a stripping device on the immersing device adapted to engage and strip the carrier when the immersing device is released, said stripping device comprising a pivoted member projecting forwardly beyond the immersing device, and adapted to engage the carrier with a scraping sliding motion.

11. In a photographic print treating apparatus, the combination with a frame, and a fluid bath supported thereby, of a conveyer arranged to travel across the bath and provided with a print carrier, consisting of a bar having impaling pins thereon projecting in the direction of travel, a swinging immersing device normally depending into the bath but adapted to be raised by the conveyer while the print carrier passes beneath it, means near the end of the bath for reversing the travel of the conveyer and carrier, and a pivoted stripping device projecting forwardly from the immersing device and adapted to be engaged by the carrier bar during its reversing movement, as the immersing device is released.

12. In a photographic print treating apparatus, the combination with a frame and a fluid bath supported thereby, of a yoke pivoted on the frame and carrying a depending swinging immersing device normally occupying the bath, said yoke being stationary during normal operating swinging movement of said immersing device and being adapted to be swung to an upright position to carry the immersing device to an accessible position out of the bath.

13. In a photographic print treating apparatus, the combination with a frame and a fluid bath supported thereby, of a conveyer arranged to travel over and across the bath, a print carrier on the conveyer having print impaling pins projecting in the direction of travel of the conveyer, means near the end of the bath for reversing the direction of travel of the conveyer, and reversing the direction of projection of the pins, and a swinging device on the frame actuated by the conveyer to wipe against the print in the said reverse direction to disengage it from the carrier as the latter is reversed.

14. In a photographic print treating machine having a developing bath, a water bath and a hypo bath, an intermittently movable conveyer for carrying a print through said baths, and a retarding roll in said water bath for preventing displacement of the print

from said conveyer when said conveyer stops moving.

15. In a photographic print treating apparatus, the combination with a plurality of baths, of endless conveying mechanism movable repeatedly through an endless path of travel and including a plurality of print engaging devices traversing said baths, means for delivering successive prints to said conveying mechanism to be picked up by said engaging devices, a continuously running motor, means including a clutch for connecting said motor to said conveying mechanism, means for closing said clutch to drive said conveying mechanism to carry successive prints forwardly from said delivering means through said baths, means for automatically opening said clutch to halt movement of said conveying mechanism when prints engaged by certain of said engaging devices are immersed in certain of said baths, and means for disengaging prints from said engaging devices.

16. In a photographic print treating apparatus, the combination with print holding means for supporting a print in position to be picked up, of a plurality of print treating baths, of an endless member movable through an endless path of travel passing adjacent said holding means and said baths, a plurality of print engaging devices mounted on said endless member at substantially uniform intervals, the distance between two of said devices being substantially equal to the distance along the path of travel of said endless member from one of said baths to another of said baths, said endless member being normally at rest in position such that a print engaged by one of said devices will be in one bath and a print engaged by another of said devices will be in a second bath, mechanism including a motor and a clutch engageable at will for moving said endless member, and means for automatically opening said clutch to stop movement of said endless member when said member has moved through a distance substantially equal to the distance from one of said engaging devices to another of said devices, so that the first mentioned print will be moved into and brought to rest in the second bath and a fresh print may be moved into and brought to rest in the first bath.

17. In a photographic print treating apparatus, the combination with a plurality of print treating baths, of an endless member movable through an endless path of travel, a plurality of print engaging devices mounted on said endless member at substantially uniform intervals, the distance between two of said devices being substantially equal to the distance along the path of travel of said endless member from one of said baths to another of said baths, said endless member being normally at rest in position such that a print engaged by one of said devices will be in one

bath and a print engaged by another of said devices will be in a second bath, driving means for said endless member including a continuously running motor and a clutch, mechanism operable at will for closing said clutch to render said driving means effective to move said endless member, and means for automatically opening said clutch to stop movement of said endless member when said member has moved through a distance substantially equal to the distance from one of said devices to another of said devices, so that the first mentioned print will be moved into and brought to rest in the second bath and a fresh print may be moved into and brought to rest in the first bath.

18. In a photographic print treating apparatus, the combination with a plurality of print treating baths, of an endless member movable through an endless path of travel, a plurality of print engaging devices mounted on said endless member at substantially uniform intervals, each of said engaging devices comprising print impaling pins normally extending in a generally forward direction relative to the direction of movement of said endless member, means for reversing the direction of said pins at one point to provide a print removing station, the distance between two of said engaging devices being substantially equal to the distance along the path of travel of said endless member from one of said baths to said print removing station and from one of said baths to another of said baths, and means for driving said endless member and for automatically stopping movement of said member when said member has moved through a distance substantially equal to the distance from one of said devices to another of said devices, so that at each movement of said endless member, a print carried by one of said engaging devices will be moved from one of said baths to said print removing station and a print carried by another of said engaging devices will be moved from one of said baths to another of said baths.

19. In a photographic print treating apparatus, the combination with a liquid bath, of conveying mechanism including a print engaging device having a path of travel above said bath, a print submerging member having its effective submerging position below said path of travel, and a link mounted for oscillation about an axis above said path of travel and pivotally connected to said submerging member, so that said engaging device during its movement will contact with said link and oscillate it to raise said member to a position above said path of travel.

20. In a photographic print treating apparatus, the combination with a liquid bath, of conveying mechanism including a print engaging device having a path of travel above said bath, a print submerging member having its effective submerging position below

10 said path of travel, said submerging member having a curved end, and a link mounted for oscillation about an axis above said path of travel and pivotally connected to said submerging member adjacent said curved end, said link having a guiding surface substantially tangent to said curved end in one position of said link relative to said member, so that said engaging device during its movement will contact with said link and ride along the guiding surface thereof to oscillate the link to raise said member to a position above said path of travel, and will ride smoothly from said guiding surface to said member and along the bottom thereof to hold said member in elevated position.

15 21. In a photographic print treating apparatus, the combination with a liquid bath, of conveying mechanism including a print engaging device having a path of travel above said bath, print submerging means mounted for movement from a position above said path of travel to an effective submerging position, and print disengaging means mounted 25 on said submerging means for disengaging a print from said print engaging means.

20 22. In a photographic print treating apparatus, the combination with a liquid bath, of conveying mechanism including a print engaging device having a path of travel above said bath, print submerging means including a member mounted for movement from a position above said path of travel to an effective submerging position below said path 35 of travel and a supporting link pivoted to said member and mounted for oscillation about an axis above said path of travel, and print disengaging means pivotally mounted on said submerging means for disengaging 40 a print from said print engaging means.

45 23. In a photographic print treating apparatus, the combination with a liquid print treating bath, of a support mounted for movement relative to said bath, said support having a normal stationary position, and a print submerging device movably mounted on said support, said submerging device when said support is in said normal position being movable to and from an effective print submerging position, said support being movable from said normal stationary position to a 50 position in which the print submerging device mounted thereon is removed from said bath to render said device and said bath freely accessible.

55 24. In a photographic print treating apparatus, the combination with a liquid print treating bath, of a support pivotally mounted for movement relative to said bath, said support having a normal stationary position, a pair of links pivotally mounted on said support, and a print submerging member mounted on said links, said submerging member when said support is in said normal position being movable to and from an effective print

submerging position by swinging said links, said support being oscillatable from said normal stationary position to a position in which said links and print submerging member are removed from said bath to render said member and said bath freely accessible. 70

75 25. Photographic print treating apparatus comprising, in combination, a developing bath, a washing bath, a fixing bath, and conveying mechanism for passing a print successively through said developing and washing baths and to said fixing bath, said conveying mechanism having a path of travel entirely out of contact with fixing solution. 80

85 26. Photographic print treating apparatus comprising, in combination, means for holding a print, a developing bath, a washing bath, a fixing bath, and endless conveying mechanism having a path of travel extending from said holding means through said developing bath and said washing bath and over said fixing bath and back to said holding means, said path of travel being entirely out of contact with fixing solution and said conveying mechanism being effective to carry a print from said holding means successively through said developing and washing baths and to said fixing bath. 90

95 27. Photographic print treating apparatus comprising, in combination, a dark chamber, a developing bath within said dark chamber, a washing bath also within said dark chamber, a fixing bath exposed to light, and conveying mechanism effective to convey a photographic print from said developing bath to said washing bath and to maintain said print immersed in said washing bath for a substantial length of time sufficient to render said print temporarily unaffected by light and then to deliver said print to said exposed fixing bath. 100 105

110 28. Photographic print treating apparatus comprising, in combination, a dark chamber, a developing bath within said dark chamber, a washing bath also within said dark chamber, a fixing bath exposed to light, and conveying mechanism effective to convey a photographic print from said developing bath to said washing bath and to maintain said print immersed in said washing bath for substantially the same length of time that said print was in said developing bath to render said print temporarily unaffected by light and then to deliver said print face upwardly to said exposed fixing bath. 115 120

125 29. Photographic print treating apparatus comprising, in combination, means for holding a print, a dark chamber, a developing bath within said dark chamber, a water bath also within said dark chamber, a fixing bath exposed to light, and endless conveying mechanism having a path of travel extending from said holding means through said developing and water baths and to said fixing bath and back to said holding means, said

conveying mechanism being effective to carry a print along said path of travel from said holding means through said developing bath and into said water bath and to maintain said print in said water bath for a substantial length of time sufficient to render said print temporarily unaffected by light and then to deliver said print to said exposed fixing bath.

30. Photographic print treating apparatus comprising, in combination, a dark chamber, a developing bath within said dark chamber, a washing bath also within said dark chamber, a fixing bath exposed to light, and conveying mechanism effective to convey 10 a photographic print from said developing bath to said washing bath and to maintain said print immersed in said washing bath for a substantial length of time sufficient to render said print temporarily unaffected by 20 light and then to deliver said print to said exposed fixing bath, said conveying mechanism having a path of travel entirely out of contact with fixing solution.

31. Photographic print treating apparatus 25 comprising, in combination, means for holding a print, a dark chamber, a developing bath within said dark chamber, a water bath also within said dark chamber, a fixing bath exposed to light, and endless conveying 30 mechanism having a path of travel extending from said holding means through said developing and water baths and to said fixing bath and back to said holding means, said path of travel being entirely out of contact 35 with fixing solution and said conveying mechanism being effective to carry a print along said path of travel from said holding means through said developing bath and into said water bath and to maintain said print 40 in said water bath for a substantial length of time sufficient to render said print temporarily unaffected by light and then to deliver said print to said exposed fixing bath.

32. The method of treating a photographic 45 print which comprises developing the print, washing the print by placing it quiescently in a washing bath within a dark chamber for a substantial length of time, and depositing the print face upwardly in a fixing bath exposed 50 to actinic light.

33. The method of treating a photographic print which comprises developing the print, immersing the print quiescently for a substantial length of time in a water bath, and 55 depositing the print in a fixing bath exposed to actinic light.

34. Photographic print treating apparatus comprising a chute for loosely holding a print, said chute extending in a generally 60 downward direction and being substantially straight throughout the major portion of its length and being turned at an angle closely adjacent its lower end, means for delivering a photographic print to the upper end of said 65 chute so that the print tends to fall by gravity

through the chute, abutment means adjacent the lower end of the chute for contact with the lower edge of a print to support a print so that the lower portion of the print is in said angularly turned portion of the chute and the major portion of the print is in said substantially straight portion of the chute, and conveying mechanism engageable with said lower portion of the print in said angularly turned portion of the chute for with- 70 drawing said print from the chute.

CERTIFICATE OF CORRECTION.

Patent No. 1,890,325.

December 6, 1932.

John S. Greene.

It is hereby certified that error appears in the printed specification of the above numbered patent requiring correction as follows: In the drawings, Sheet 1, Fig. 10, should appear as shown below instead of as shown in the patent-

and that the said Letters Patent should be read with these corrections therein that the same may conform to the record of the case in the Patent Office.

Signed and sealed this 17th day of January, 1933.

(Seal)

M. J. Moore
Acting Commissioner of Patents.
